UNITED STATES PATENT OFFICE.

HENRY L. KINCH, OF SALINA, KANSAS.

LUBRICATOR.

SPECIFICATION forming part of Letters Patent No. 760,876, dated May 24, 1904.

Application filed March 17, 1903. Serial No. 148,243. (No model.)

To all whom it may concern:

Be it known that I, HENRY L. KINCH, a citizen of the United States, residing at Salina, in the county of Saline, State of Kansas, have invented certain new and useful Improvements in Lubricators; and I do hereby declare the following to be a full, clear, and exact description of the invention, such as will enable others skilled in the art to which it appertains to make and use the same.

This invention relates to lubricators for steam-engines, and has for its object to provide a device of this nature which will be automatically regulated to admit different amounts of the oil to the cylinders and which will utilize the exhaust-steam from the engine to accomplish this object.

Other objects and advantages of the invention will be understood from the following description.

In the drawings forming a portion of this specification, and in which like numerals of reference indicate similar parts in the several views, Figure 1 is a side elevation of the device. Fig. 2 is a central longitudinal section showing the device in operation under low exhaust-pressure and with the reservoir partially empty. Fig. 3 is a view similar to Fig. 2, showing the device in its inoperative position with the exhaust-valve closed and with the follower-engaging catch in its operative position. Fig. 4 is an end view of the reservoir, showing the catches 15; and Fig. 5 is a detail view of the bell-crank lever.

Referring now to the drawings, the present device comprises a reservoir 5 for the reception of lubricant having a filling-opening 6, provided with a screw-cap 6', an air-inlet 7, and a drain-cock 8. Disposed within the reservoir is a follower 9, attached to a plunger 10, passing through an opening 11 in a screw-cap 5', disposed upon one end of the reservoir. The opening 11 is threaded and is provided with a bushing 12, having a flange 12' on either end thereof, said bushing being adjustable into and out of the reservoir to vary the tension of a spring 13, disposed about the plunger between the inner flange 12' and the follower 9. The plunger 10 has a reduced portion 14 adjacent to its inner end and re-

sulting in shoulders 14'. Attached to outer flange 12' of the bushing 12 are a pair of sliding catches 15, which may be engaged with the shoulders 14' when the plunger 10 is at the limit of its outward motion to prevent its return. In the opposite end 5" of the reservoir is an outlet-opening 16, having an elbow 17 connected therewith, said elbow being provided with an ordinary form of stuffing-box to receive the sight-glass 18, the upper end of which is disposed in a second stuffing-box 18', from which a connection leads to the cylinders of the engine. The elbow 17 also contains the seat 19 of a needle-valve, the needle 20 of which enters through the bottom 65 of the elbow. This needle 20 is adjustable in a collar 21, pivoted between the jaws 22 of a bell-crank lever 23, journaled in a bracket 24 upon the bottom of the reservoir. The bell-crank lever 23 has a perforation therethrough 70 at a point between the needle-valve and the bracket 24, through which freely passes a threaded rod 25, the upper end of which is attached to the elbow 17. Disposed between the lever 23 and a thumb-nut 26, engaged with the threads of the rod 25, is a spring 27, which normally holds the lever 23 raised and the needle 20 in engagement with the seat 19, to close the valve and to prevent the egress of the oil from the reservoir. 80

Attached to one side of the reservoir 5 by means of brackets 28 and 29 is a cylinder 30, having a piston 31 disposed therein, which piston is attached to the end of a piston-rod 32, the outer end of which is pivotally connected with one end of the bell-crank lever 23. The cylinder 30 has an opening 33 in the side thereof, with which is engaged an exhaust-pipe 34 of the engine. The cylinder 30 is also provided with an outlet-opening 35, 90 which is of lesser diameter than the exhaust-pipe 34.

In the operation of this invention the plunger 10 is drawn outwardly through the bushing 12 until the reduced portion 14 clears the end thereof, when the catches 15 may be engaged with the shoulders 14' to hold the follower 9 at the limit of its motion. Oil is then introduced into the reservoir through the opening 6, which is then closed by means of the screw- 100

cap 6'. The catches 15 are then disengaged from the shoulders 14', and the pressure exerted by the spring 13 is put upon the oil, which is prevented from leaving the reservoir 5 by the needle 20, which is held in engagement with the seat 19 by the spring 27. Should the engine now be started, the exhaust-steam from the cylinders passing through the pipe 34 would enter the cylinder 30 and would 10 cause sufficient pressure to move the piston 31 therein. This movement of the piston 31, through the medium of the piston-rod 32, is communicated to the lever 28, which is moved against the action of the spring 27, moving 15 the needle 20 from the seat 19 and permitting the egress of a quantity of oil from the reservoir which will pass upwardly through the sight-glass 18 to the cylinders of the engine. It will of course be understood that under certain 20 conditions—say when the engine is exerting its greatest amount of power—the pressure in the cylinder 30 will be greater than at other times, which will act to move the piston 31 a greater distance and admit a larger 25 supply of oil to the cylinders. When the engine is stopped, the pressure in the cylinder 30 will of course be removed, and the valve will be closed through the action of the spring 27.

In practice modifications of the specific construction shown may be made, and any suitable materials and proportions may be used for the various parts without departing from the spirit of the invention.

What is claimed is—

- 35 1. A lubricator for engine-cylinders comprising a reservoir for the reception of the lubricant, said reservoir having an inlet-port and an outlet-port, a closure for the inlet-port, a valve for the outlet-port, a pipe connecting the outlet-port with the cylinder of the engine, means for forcing the lubricant from the reservoir, a cylinder having a larger and smaller opening therein, a piston disposed within the cylinder, connections between the piston and the valve of the outlet-port for operation of the latter by movement of the former and a pipe connection between the larger opening of the cylinder and the exhaust-port of the

engine to admit steam to said cylinder for movement of the piston.

2. A lubricator for engine-cylinders comprising a reservoir for the reception of a lubricant, said reservoir having an inlet-port and outlet-port, a closure for the inlet-port, a lubricant-conducting pipe attached to the outlet-port connecting with the cylinder of an engine, means for forcing the lubricant from the reservoir, a valve in said pipe, a valve-actuating cylinder having a larger and smaller opening therein, said larger opening being connected with the exhaust-port of the engine for the admission of the steam to said actuating-cylinder, a piston disposed within said cylinder, to be operated by the steam, a rod attached to the piston and passing out of the cylinder 65 through an opening in the end thereof, a connection between the end of the rod and the valve of the elbow for operation of the latter by movement of the former, and means for holding the valve normally closed.

3. A lubricator for engine-cylinders comprising a reservoir for the reception of a lubricant, said reservoir having an inlet-port and an outlet-port, a closure for the inlet-port, an elbow attached to the outlet-port and having 75 an opening therethrough for the passage of the lubricant, a pipe connecting the elbow with the cylinder of an engine, a valve in the elbow to close the passage, means for holding the valve normally closed, means for forcing 80 the lubricant from the reservoir, a cylinder having a larger and smaller opening therein, said larger opening having a pipe connection with the exhaust-port of the engine, a piston disposed within the cylinder to be operated 85 by the exhaust-steam from the engine and connection between the piston and valve to operate the latter against the action of the closing means.

In testimony whereof I affix my signature in 90 presence of two witnesses.

HENRY L. KINCH.
